CLAIM

The ornamental design for a speaker enclosure, as shown and described.

DESCRIPTION

FIG. 1 is a view of the right end of the speaker enclosure. FIG. 2 is a view of the rear of the speaker enclosure. FIG. 3 is a view of the bottom of the speaker enclosure. FIG. 4 is a view of the left end of the speaker enclosure. FIG. 5 is a view of the front of the speaker enclosure. FIG. 6 is a view of the top of the speaker enclosure. FIG. 7 is a right end-top-front view of the speaker enclosure. FIG. 8 is a left end-bottom-front view of the speaker enclosure. FIG. 9 is a right end-bottom-front view of the speaker enclosure; and, FIG. 10 is a left end-top-front view of the speaker enclosure. The broken lines depict environment that forms no part of the claimed design.
